RAILWAY TRACK CIRCUIT APPARATUS

Arthur E. Dodd, Edgewood, Pa., assignor to The Union Switch & Signal Company, Swissvale, Pa., a corporation of Pennsylvania

Application May 31, 1941, Serial No. 395,925

7 Claims. (Cl. 175—320)

My invention relates to railway track circuit apparatus, and it has particular reference to the organization of apparatus into railway track circuits of the class wherein improved operating characteristics are obtained by varying the energization of the track relay after it has picked up.

Railway track circuits are arranged in such manner that the track relay is controlled by an application of a shunt which decreases the energy available at the relay to hold it picked up. This factor of controlling a relay by the application of a shunt rather than by opening or interrupting the circuit, generally results in providing the relay with characteristics that make it slow to release and quick to pick up, inasmuch as the pick-up energy level of a relay ordinarily is much higher than the drop-away level at which the relay releases. In order, therefore, for a train shunt to be effective to release the relay, the shunt must be sufficiently low in resistance to shunt away from the relay winding the increment of energy above the drop-away energy level of the relay. This shunt, however, provides a low resistance or short circuit path across the relay winding which maintains the flux in the relay for an appreciable interval of time, so that a correspondingly long time interval is required for even a low resistance train shunt to lower the energy level of the relay below its drop-away value. Hence, if the train shunt varies intermittently in effectiveness, the release period of the relay might be materially increased and after the relay releases due to a shunt, there is a possibility that these variations in shunt might cause the relay to be picked up and released and thus follow the fluctuations in the applied shunt. The tendency of ordinary relays to follow varying train shunts, and the slow releasing characteristics possessed by such relays when shunted, are undesirable in track relays since such relays often are incorporated into signaling or control systems not only for controlling signal indications, but also for establishing directional control in accordance with the sequence in which the relays of two or more successive sections are released. It is apparent, therefore, that if a relay is improperly picked up in response to a momentary loss of train shunt, or if the relay of a section vacated by a train picks up prior to the train causing the release of the relay of the section in advance, an improper directional set-up might be established as well as causing flashing signal indications, etc. Furthermore, such relays are often employed for electrically locking signals and

switches against operation, and if a track relay is intermittently released and picked up due to a varying train shunt in its section, the effectiveness of such locking is materially decreased.

5 I am aware that schemes have been proposed heretofore to condition a track relay to create its pick-up energy level when it is released, and to reduce the energy level in the relay after it has picked up, thereby obtaining a track circuit having high shunting characteristics. One of the 10 most effective of such schemes is to employ a secondary relay, which ordinarily is slow to pick up, controlled by the track or primary relay and in turn controlling the release sensitivity of the track relay. Such systems commonly are termed 15 primary-secondary track relay combinations, and although they materially improve the operation of track relays and track circuits, the use of two independent relays increases the initial and 20 maintenance cost of such track circuit arrangement to a considerable extent.

In view of the foregoing and other important 25 considerations, it is an object of my invention to provide a track relay having means for controlling its own release sensitivity in such manner that the relay is conditioned to create its proper pick-up energy level when released, and when picked up the energy level in the relay is reduced to a value only slightly above that required to 30 hold its armature in its attracted position.

Another object of my invention is to provide a railway track circuit incorporating a track relay having means for incorporating into a single relay structure the functions of the two relays of a 35 primary-secondary relay combination.

A further object of my invention is the provision of railway track circuit apparatus incorporating relays having means for delaying the pick-up of the armatures of such relays.

40 An additional object of my invention is the provision of safe, reliable, and relatively inexpensive means for obtaining in a single relay the benefits and advantages of a primary-secondary relay combination.

45 Another object of my invention is the provision of novel and improved forms of electrical relays arranged to be slow to pick up and having quick release characteristics when shunted.

The above-mentioned and other important 50 objects and characteristic features of my invention which will become readily apparent from the following description, are attained in accordance with my invention by incorporating into a track relay a retaining winding coupled to a track circuit and arranged to oppose the attractive action

of the operating winding of the relay on its armature, and by utilizing a make-before-break contact combination operated by such armature to control the energy level created by the operating winding. The coupling of the retaining winding 11 of the relay to the track circuit is effected in accordance with my invention in such manner that the decay of flux due to current in the operating winding is not effected, but the growth of flux is prolonged to provide the relay with slow pick-up characteristics.

I shall describe four forms of apparatus embodying my invention, and shall then point out the novel features thereof in claims.

In the accompanying drawing, Fig. 1 is a diagrammatic view showing a preferred form of apparatus embodying my invention. Figs. 2, 3 and 4 are diagrammatic views each illustrating a modified form of the apparatus shown in Fig. 1, and each also embodying my invention.

In each of the several views of the drawing, similar reference characters have been employed to designate corresponding parts.

Referring first to Fig. 1, the reference characters 1 and 1a designate the track rails of a stretch of railway track divided by insulated joints 2 into an insulated section D—E. Section D—E is provided with a track circuit comprising a suitable source of current, such as a battery TB, connected in series with the usual current limiting resistor 3, across the rails 1 and 1a at one end D of the section, and at times only a portion and at other times the entire operating winding of a relay TR connected across the track rails at the other end E of the section.

Relay TR comprises a magnetizable core 5 provided with an operating winding 6, another magnetizable core 10 provided with a retaining winding 11, and armature means comprising two armatures 7 and 8 disposed in magnetic relation to cores 5 and 10, respectively, and connected together by means of a rigid non-magnetic member 9. The armature means are biased, as by gravity, into a released or back position wherein armature 8 engages core 10, and are operated to a front or picked-up position in response to the attractive action on armature 7 of the flux due to current in winding 6. This operation of the armature means is at times opposed by the attractive action on armature 8 of flux due to current in retaining winding 11. Armature 7 is pivoted at 4 in the usual manner and has associated therewith a plurality of contact members 12, 13 and 14 which cooperate with the usual front and back contact points to form front and back contacts according as armature 7 is in its picked-up or released position, respectively. One of the contact members 12 is bifurcated and functions as the common or bridging member of a make-before-break contact arrangement. When armature 7 is in its attracted position, a portion only of winding 6 is connected across the track rails 1 and 1a at E over an obvious circuit including front contact 12—15 and a resistor 17, and when armature 7 is released, the entire operating winding 6 is connected to the track rails over an obvious circuit including back contact 12—16.

The retaining winding 11 is coupled with the track circuit in such manner as to provide the relay with slow pick-up characteristics. Various means are provided to effect this coupling. In Fig. 1, for example, the retaining winding is coupled to the track circuit through the medium of a secondary winding 18 disposed on core 5 and connected to retaining winding 11 through a back

contact 13—19 of armature 7; in Fig. 2 the coupling is effected through a condenser 20 (see Fig. 2) which may, for example, be of the electrolytic type, connected in series with retaining winding 11 across the track rails 1 and 1a in multiple with winding 6 of relay TR; in Fig. 3 the coupling is effected through the medium of an auxiliary transformer 22 (see Fig. 3) having a primary winding 23 interposed in series in the connection of winding 6 of relay TR to the track rails and having a secondary winding 24 connected over back contact 13—19 of armature 7 to retaining winding 11; and in Fig. 4 the coupling is also effected by means of auxiliary transformer 22.

The operation of the apparatus illustrated in Fig. 1 is as follows: When section D—E is unoccupied, armature 7 of relay TR is in its attracted or upper position as shown in the drawing, and in this position of armature 7 front contact 12—15 of relay TR is closed to complete the obvious circuit path which connects resistor 17 and a portion of coil 6 of relay TR across the rails 1 and 1a. The parts of relay TR preferably are designed and proportioned in such manner that with only a portion of coil 6 energized, an energy level only sufficiently above the release value of the relay to assure reliable operation of such relay under the various ballast conditions, is created in the relay due to current supplied to the portion of coil 6 of the operating winding from the rails 1 and 1a.

When a train enters section D—E, the current supplied from the battery TB to the rails 1 and 1a is shunted away from the operating winding 6 of relay TR. Since the relay armature is held attracted by an energy level only slightly in excess of its release value, the shunt applied to the relay causes the energy level in the relay to decrease and as a result armature 7 quickly drops to its released position, wherein contact members 12, 13 and 14 engage their respective back contact points. During the travel of armature 7 from its attracted to its released position, contact member 12 makes engagement with back contact point 16 prior to breaking engagement with front contact point 15, thereby avoiding opening of the relay circuits.

In the released position of armature 7 of relay TR, back contact 13—19 is closed to connect retaining winding 11 to secondary winding 18 disposed on core 5. Also, resistor 7 is placed on open circuit and the entire operating winding 6 of relay TR is connected across the track rails 1 and 1a over back contact 12—18, thereby conditioning the relay to create its pick-up energy level. When the train shunt is removed from relay TR, as for example, when the train vacates section D—E or when the shunt is momentarily "lost" due to rail film conditions or other poor shunting conditions, current from battery TB is supplied through rails 1 and 1a to the entire operating winding 6 of relay TR. During the building up of flux in core 5 due to such current, an electromotive force is induced in the secondary winding 18 disposed on core 5 and is applied through back contact 13—19 to retaining winding 11. The flux set up due to current in winding 11 threads armature 8 to hold that armature down and thus opposes the action on armature 7 of the flux due to current in winding 6. If the energization of the relay operating winding is caused by the train vacating the section, the action of winding 11 in opposing the pick-up effect of the flux due to current in winding 6 functions to maintain armature 7 released until

the flux condition in core 5 reaches substantially a constant state condition so that no electromotive forces are induced in secondary winding 18. This steady state flux condition in core 5 substantially corresponds to the pick-up energy level 5 of the relay, and since under the condition of flux equilibrium in core 5 no current is induced in winding 18, the attractive effect of the flux due to current in winding 6 on armature 7 is no longer opposed by the attractive effect on armature 8 of flux due to current in winding 11, with the result that armature 7 is operated to its 10 picked-up position wherein back contact 13-19 is opened to disconnect retaining winding 11 from secondary winding 18, and contact member 12 is 15 operated from its released to its attracted position to form front contact 12-15 prior to breaking engagement with back contact point 16. The closing of front contact 12-15 connects resistor 17 in circuit with a portion of operating winding 11 in circuit with a portion of operating winding 6 of relay TR across the track rails 1 and 1a, hence armature 7 of relay TR is held in its attracted position by virtue of the energization of only a portion of the operating winding 6 of relay TR and the energy level of the relay accordingly is reduced to a value only slightly greater than the release value of the relay, as was pointed out heretofore. Resistor 17 is selected to have a resistance substantially equal to the resistance of the portion of winding 6 that is cut out when the relay is picked up, hence the resistance of the relay is substantially the same in both its released and picked-up positions, and the percentage reduction of flux, effected when the relay is picked up, is caused to be independent of the track circuit length and adjustment. Relay TR accordingly is caused to be slow to pick up, and when the train vacates its associated section, the pick-up of the associated relay is delayed for an interval sufficient to enable the train to shunt the relay of the section in advance and cause such advance track relay to be released to establish the proper directional set-up, signal control, locking, or other function wherein it is required for proper operation that the advance relay be released prior to the rear relay picking up.

In the event that armature 7 of relay TR is released so that its entire operating winding 6 is connected in circuit with the track rails, and current is supplied from the rails to such winding due to a loss of shunt in section D-E, then retaining winding 11 is energized by current supplied from secondary winding 18 during the building up of flux in core 5 and armature 7 is held down due to the attractive effect on armature 8 of flux due to current in retaining winding 11. This hold-down effect of winding 11 prevents armature 7 of relay TR from picking up immediately on a loss of shunt, and provides a delayed pick-up period for relay TR sufficient under normal conditions to enable the train shunt to be restored and the winding 6 again to be shunted prior to armature 7 being attracted from its released to its picked-up position. It can be seen, therefore, that the delayed response characteristics of a relay of the class illustrated in Fig. 1 prevents improper operation of the relay due to a momentary loss of train shunt in its associated section.

It should be noted that the contacts operated by contact member 12 of relay TR function as make-before-break contacts during the travel of the relay armature from its released to its picked-up position, that is, front contact 12-15 is closed prior to back contact 12-16 being 75 closed in Fig. 1 to provide slow pick-up char-

opened. In addition, the operation of these contacts is effected by the travel of armature 7 from its released to its picked-up position only after the pick-up energy level is created in the relay, hence armature 7 is attracted in response to a relatively high energy level available in the relay and moves rapidly due to the magnetic force present in the relay. The momentum developed due to the rapid movement of armature 7 is, therefore, sufficient to carry the armature to its fully attracted position even though the energy level in the relay is reduced when back contact 12-16 opens. With armature 7 in its fully attracted position, the reduced energy level available in the relay after front contact 12-15 closes is effective to maintain the armature in its picked-up position.

In addition, it should be noted that secondary winding 18 disposed on relay core 5 is open circuited at all times except when back contact 13-19 of the relay is closed and it follows that when armature 7 is picked up, winding 18 cannot operate to delay the decay of relay flux such as might happen if winding 18 were connected at 25 all times in circuit with retaining winding 11.

I have represented in Fig. 2 a modified arrangement of the relay shown in Fig. 1, wherein retaining winding 11 is coupled to the track circuit through a condenser 20 which is charged 30 when the section becomes unoccupied, and which discharges through retaining winding 11 and the train shunt when the section becomes occupied. During the interval that condenser 20 becomes charged, winding 11 is energized and functions 35 to hold down armature 8 and thus oppose operation of armature 7. For example, when relay TR is shunted, armatures 7 and 8 are released and condenser 20 is discharged. When the shunt is removed, the charging current of the condenser flows through retaining winding 11 and of course is effective to energize winding 11 to create flux which tends to hold armature 8 in its released position against the attractive effect on armature 7 of flux due to current in winding 6, thereby rendering the relay slow to pick up. When the section becomes occupied, the condenser discharges through winding 11 and the low resistance train shunt, but this action has little or no effect upon operation of the relay at this time other than to condition the condenser to become charged again when the section becomes vacated. It is, of course, readily apparent that by properly proportioning condenser 20, the relay shown in Fig. 2 may be provided with slow pick-up characteristics substantially similar to those pointed out in connection with relay TR of Fig. 1. It is further apparent that the relay shown in Fig. 2 functions to vary the energy level in the relay after it picks up in 60 substantially the same manner that such energy level is varied by the apparatus represented in Fig. 1.

The apparatus represented in Fig. 3 illustrates a further modification of the apparatus of Fig. 1 wherein retaining winding 11 is coupled to the track circuit by means of a transformer 22 having its primary winding 23 interposed in the connection of winding 6 to the track rails. Secondary winding 24 of transformer 22 is connected to retaining winding 11 when back contact 13-19 is closed, and it is readily apparent that the apparatus shown in Fig. 3 will operate in substantially the same manner as that illustrated in Fig. 1 to provide slow pick-up char-

teristics and vary the energy level of the relay after it picks up.

A still further modification of the apparatus illustrated in Fig. 1 is represented in Fig. 4, wherein a polarized relay TR1 is interposed in a polarized track circuit supplied with unidirectional current of one relative polarity or another from battery TB according as pole changing contacts 26 and 27 are in their picked-up or released positions, respectively. Relay TR1 is arranged to retain its neutral armature 7 in its picked up position during reversals of current polarity, and is provided with at least one polar contact member 29 arranged to be controlled in the manner usual in polarized relays in accordance with the polarity of current energizing operating winding 6 of the relay.

Relay TR1, as shown, is provided with an auxiliary magnetic structure 30 carrying retaining winding 11 and provided with a core extension 10 arranged to hold down armature 8 when winding 11 is energized. Core extension 10 of relay TR1 therefore corresponds to auxiliary cores 10 shown in Figs. 1, 2 and 3. When armature 7 of relay TR1 is in its upper attracted position, armature 8 is operated into magnetic relation to core 30 so that when winding 11 is energized, armature 8 is attracted to core 30 and functions to hold armature 7 in its upper position. Winding 11 is connected to secondary winding 24 of transformer 22 which has its primary winding 23 interposed in the connection of operating winding 6 of relay TR1 to the track rails. Relay TR1 also incorporates the make-before-break contact arrangement hereinbefore described and by means of which the energy level in the relay is varied according as the relay is released and picked up.

When section DE is unoccupied and pole changing contacts 26 and 27 are in their upper positions as shown in the drawing, current of one relative polarity which I shall term positive polarity is supplied through the track rails 1 and 1a to a portion of operating winding 6 of relay TR1. The parts of relay TR1 are so proportioned that with only a portion of winding 6 energized, the energy level created in the relay is sufficient to hold neutral armature 7 in its upper attracted position, and with relay TR1 energized with current of normal polarity, polar contact member 29 is operated to its normal or left-hand position, as viewed in the drawing.

If, now, pole changing contacts 26 and 27 operate to their released positions, current of the opposite or reverse polarity is applied through transformer 22 to operating winding 6 of relay TR1. During the interval of flux reversal in transformer 22, an electromotive force is induced in secondary winding 24 of the transformer and is applied to retaining winding 11 to energize that winding and attract auxiliary armature 8. The parts of relay TR1 are so proportioned that the energization of retaining winding 11 effected due to a reversal of current in winding 23 of transformer 22 is effective to hold armature 8 in its upper position until the flux in core 5 builds up to its value sufficient to hold armature 7 in its attracted position. It follows, therefore, that neutral armature 7 of relay TR1 is held in its upper attracted position during the intervals of current reversals in the track circuit. Under the assumed conditions, polar contact member 29 will of course be caused to operate to its reverse or right-hand position, as viewed in Fig. 1.

When section D—E becomes occupied by a train, the current supplied from battery TB is 75

shunted away from operating winding 6 of relay TR1 and neutral armature 7 releases to open front contact 12—15 and close back contact 12—16, the closing of this latter contact connecting the entire operating winding 6 of relay TR1 in circuit with the track rails. When the section becomes vacated, therefore, the entire operating winding of relay TR1 is available to create flux and pick up neutral armature 7. 10 However, the energization of operating winding 6 of relay TR1 causes the induction in secondary winding 24 of transformer 22 of an electromotive force which energizes winding 11 and causes flux to thread core extension 10 and armature 8 to hold armature 7 down against the attractive effect of flux due to current in winding 6. After the current in winding 6 attains substantially a constant state condition, winding 11 becomes de-energized and no longer opposes the attractive effect of flux due to current in winding 6 on armature 7, so that the armature moves rapidly from its released to its attracted position, thereby opening back contact 12—16 and closing front contact 12—15. The closing of front contact 12—15 of course results in the energization of only a portion of operating winding 6 of relay TR1, and the energy level created in the relay is therefore reduced to a value only slightly greater than the release value of the relay. It follows, therefore, that relay TR1 is made slow to pick up, is held in its attracted position during intervals of reversals of current polarity in the operating winding of the relay, and the energy level in the relay is varied according as the relay is released or picked up in order to attain more satisfactory shunting characteristics for the relay.

Although I have herein shown and described only four forms of track circuit apparatus embodying my invention, it is understood that various changes and modifications may be made therein within the scope of the appended claims without departing from the spirit and scope of my invention.

Having thus described my invention, what I claim is:

1. In combination, a magnetizable core, armature means disposed in magnetic relation to said core and provided with contacts including a make-before-break contact combination comprising a front contact and a back contact with a bridging member which causes both said contacts to become closed momentarily during the movement of said armature means from its released to its attracted position, an operating winding disposed on said core and effective when energized to actuate said armature means from its released to its picked-up position, a control circuit connected to a portion only of said operating winding over said front contact and to the entire operating winding over said back contact, a retaining winding disposed to be effective when energized to oppose the attractive action of said operating winding on said armature means, and a condenser connected in series with said retaining winding across said control circuit in multiple with said operating winding.

2. In combination, a magnetizable core, armature means disposed in magnetic relation to said core and provided with contacts including a make-before-break contact combination comprising a front contact and a back contact with a bridging member which causes both said contacts to become closed momentarily during the movement of said armature means from its released to its attracted position, an operating winding

disposed on said core and effective when energized to actuate said armature means from its released to its picked-up position, a control circuit connected to a portion only of said operating winding over said front contact and to the entire operating winding over said back contact, a retaining winding disposed to be effective when energized to oppose the attractive action of said operating winding on said armature means, and a transformer having a primary winding interposed in the connection of said operating winding to said control circuit and having a secondary winding connected to said retaining winding over a back contact operated by said armature means.

3. In combination, a magnetizable core, an armature disposed in magnetic relation to said core, an operating winding on said core for actuating said armature, contacts operatively connected to said armature and operated from one position to another in response to energization of said operating winding, a control circuit connected to a portion only of said operating winding over a contact of said armature closed in its said other position and connected to the entire operating winding over a contact of said armature closed in its said one position; and a retaining winding supplied with current during a growth of flux in said core due to current in said entire operating winding, said retaining winding being disposed so as to be effective when energized to retain said armature in its said one position in opposition to the attractive action of said operating winding on said armature.

4. In combination with a control circuit, a magnetizable core, an armature disposed in magnetic relation to said core, an operating winding connected to said control circuit and disposed on said core for actuating said armature, contacts operatively connected to said armature and including a front contact operated from an open to a closed condition in response to operation of said armature from its released to its attracted position caused by energization of said operating winding, a retaining winding inductively coupled to said control circuit when said armature is released and disposed to oppose the attractive action of said operating winding on said armature, and means controlled by said front contact for decreasing the energization of said operating winding by said control circuit, whereby said operating winding is conditioned to create a high or a low energy level in the core according as said armature is released or is picked up.

5. In combination, a magnetizable core, an operating winding disposed on said core, an armature disposed in magnetic relation to said core

and provided with contacts including a make-before-break contact combination comprising a front contact and a back contact with a bridging member which causes both said contacts to become closed momentarily during the movement of said armature from its released to its attracted position, a control circuit connected over said front contact to a portion only of said operating winding and connected over said back contact to the entire operating winding, a retaining winding disposed to oppose the attractive action of said operating winding on said armature, and a secondary winding disposed on said core and connected to said retaining winding over a back contact operated by said armature.

6. In a relay, in combination, two magnetizable cores, an armature biased away from one toward the other of said cores, an operating winding on said one core for actuating said armature to said one core, contact members controlled by said armature from one position to another in response to the energization of said operating winding, a retaining winding disposed on said other core and effective when energized to delay the response of said armature to energization of said operating winding, and means including a secondary winding disposed on said one core and a contact closed in said one position of said contact members for energizing said retaining winding.

7. In combination, two magnetizable cores, an armature biased away from one toward the other of said cores, an operating winding on said one core for actuating said armature against its bias to said one core, contacts operatively connected with said armature and operated from one position to another when said armature is actuated to said one core, a control circuit, means controlled by contacts of said armature for connecting only a portion of said operating winding with said control circuit when said contacts are in said other position and for connecting the entire operating winding with said control circuit when said contacts occupy their said one position, a retaining winding disposed on said other core, and means for supplying energy to said retaining winding during the growth of flux in said one core due to current in said entire operating winding, whereby energy in said retaining winding creates flux acting on said armature in opposition to the flux created by energy in said entire operating winding for delaying actuation of said armature from said other core to said one core.

ARTHUR E. DODD.
